DRAINBOARD FOR CLOTHES WRINGERS

Nicholas L. Etten, Waterloo, Iowa

Application July 4, 1939, Serial No. 282,823

2 Claims. (Cl. 68—264)

This invention relates to clothes wringers for domestic washing machines, and particularly to a new type of drain board for such wringers.

In the hand crank-actuated wringers of the past it was common practice to have feed boards across the face of the wringer frames adjacent the bite of the rolls to assist in properly feeding garments into the wringer. These feed boards were bow-shaped with the curved center section higher or closer to the bite of the rolls. The object of this arrangement was to spread the garments over the width of the rolls and to prevent as much as possible the bunching of garments through the center of the roll. Such feed boards were fairly effective and did much to assist the better wringer practice of spreading the garments across the width of the rolls.

Originally the electric motor driven washing machines were equipped with wood frame hand wringers merely adapted for power drive and such wringers carried the spreading feed boards. However, when special steel frame wringers were designed for power washing machines, the use of such feed boards was complicated by the steel drainboards and other structural difficulties, with the result that the use of such spread feed devices were abandoned and bunched or center feeding of wringers is now common practice.

It is the particular object of this invention to provide a spread feed device for wringers wherein in the conventional drainboard is shaped to accomplish the desired results.

Other objects and benefits will be disclosed by the following descriptions and drawings in which:

Fig. 1 is a front elevation view of a wringer equipped with spread feed drainboards;

Fig. 2 is a top plan view of the wringer shown in Fig. 1;

Fig. 3 is an end elevation view of the same wringer;

Fig. 4 is a sectional elevation view of the drainboard as it would appear on the section lines 4—4 of Fig. 2; and

Fig. 5 is a sectional end elevation view of the drainboard as it would appear on the section lines 5—5 of Fig. 1.

Now referring to the drawings, I designate by the numeral 10 the lower frame of a conventional wringer adapted to be mounted on the gear head drive by flange members 11 by means of bolts through the holes 12. This wringer has a detachable upper frame 13 and is equipped with a quick release mechanism actuated by release buttons 14. Pressure adjustment is pro-

vided by the pressure adjustment handle 15 on the top of the frame. Pressure reset for the wringer is accomplished by means of a pressure reset handle 16 on the end of the wringer. The wringer has a pair of rolls, the lower roll being designated by the numeral 17 and the upper roll by the numeral 18.

Attached to the frame of the wringer by any conventional method is a pair of drainboards 19. These drainboards have a raised upper edge 20, the edge fading out in height toward the center of the drainboard to provide a drain opening. In the center section of the drain basin there is an upwardly bowed central section 21, the highest part of the bowed section being adjacent the bite of the rolls 17 and 18, and the lowest part being adjacent the drain opening in the center of the board. On each side of the raised central section 21 are valleys 22 and 23 which provide dual drainways for water meeting at the drain opening at the front center of the drainboard. This structure will be well understood by referring to Figs. 4 and 5, which clearly show the cross section contours of the drain basin. On the inside edge of the drainboard is a flange 24 by means of which the drainboards are assembled to the frame of the wringer in any conventional manner as is well known in the art.

It will be appreciated that when a mass of clothes is inserted in the wringer as is normally done in the center of the roll, the upturned section 21 will act to spread the garments and tend to feed the clothes in both directions, crosswise of the wringer rolls and thereby materially assist in properly feeding the clothes in a thin section rather than bunched in the center of the rolls. It further will be appreciated that this raised central section will have a tendency to move the clothes from one side or the other and thereby utilize the side sections of the wringer rather than only the center section, which materially assists in spreading the wear of the rolls and preventing the common roll failure of the center of the roll being worn out and ineffective. This condition is so common that it is well-known to even the casual observer. Also, the causes are well-known and it is believed that with the above explanation the function of my drainboard will be well understood and appreciated.

Having thus described my invention, I claim:

1. In a drain board for a clothes wringer, a clothes spreading surface comprising an upwardly bowed central section of convex configuration with its highest point adjacent the center point of the rolls and lower points adjacent the end

portions of the rolls and on opposite sides of the high center portion, said bowed central section extending outwardly from a point adjacent the wringer rolls to a point remote from the rolls to exert a spreading action on clothes passing through the wringer a considerable distance before they reach the rolls, and raised marginal portions to define a pair of drain channels on opposite sides of the high central portion and direct drain water toward a center drain channel.

2. In a drain board for a clothes wringer, a clothes spreading surface comprising an upwardly bowed central section having its highest point

adjacent the center point of the rolls and lower points adjacent the end portions of the rolls and on opposite sides of the high center portion, raised marginal portions at each side of said central section, said raised marginal portions having their highest points adjacent the ends of the rolls to define a pair of drain channels on opposite sides of the high central portion, said raised marginal portions being curved toward each other and downwardly to meet in a single, narrow drain channel in the center of the drain board structure.

NICHOLAS L. ETTEN.
